United States Patent

Des. 239,235
Patented Mar. 23, 1976

239,235

SEAT

David P. G. Williams, New York, N.Y., assignor to
Futorian Corporation, Amsterdam, N.Y.

Filed Oct. 1, 1974, Ser. No. 510,980

Term of patent 14 years

Int. Cl. D6—01

U.S. Cl. D6—63

FIG. 1.

FIG. 2.

FIG. 3.

FIG. 4.

FIG. 1 is a front perspective view showing my design in the form of a sofa:

FIG. 2 is a front perspective view of my new design shown in the form of a loveseat;

FIG. 3 is a rear perspective view of the design of FIG. 1 shown in the form of an arm chair; and

FIG. 4 is a front perspective view thereof.

In each case the side of the seat not shown is a mirror image of the side shown while the backs of the various seats are conventionally plain.

I claim:

The ornamental design for a seat, as shown and described.
